Fig. 15.

Fig. 16.

Fig. 17.

FIG. 1 is a front view of a clamp-around ammeter-voltmeter showing our new design.

FIG. 2 is a right side view thereof.

FIG. 3 is a plan view thereof.

FIG. 4 is a rear view thereof.

FIG. 5 is a left side view of FIG. 1.

FIG. 6 is a bottom view thereof.

FIG. 7 is a front view of a modified form of the clamp-around ammeter-voltmeter shown in FIGS. 1 to 6 inclusive.

FIG. 8 is a left side view of FIG. 7.

FIG. 9 is a top view of FIG. 7.

FIG. 10 is a rear view thereof.

FIG. 11 is a right side view of FIG. 7.

The bottom view of the embodiment of FIGS. 7 to 11 is the same as that of FIGS. 1 to 6.

FIG. 12 is a front view of another modified form of the clamp-around ammeter-voltmeter shown in FIGS. 1 to 6 inclusive.

FIG. 13 is a left side view thereof.

FIG. 14 is a top view thereof.

The bottom, right side and rear views of the embodiment of FIGS. 12 to 14 are the same as the corresponding views of FIGS. 7 to 11.

FIG. 15 is another modified form of the clamp-around ammeter-voltmeter shown in FIGS. 1 to 6 inclusive.

FIG. 16 is a left side view of FIG. 15.

FIG. 17 is a top view thereof.

FIG. 18 is a rear view thereof.

FIG. 19 is a right side view of FIG. 15.

FIG. 20 is a bottom view thereof.

The essential features of the design reside in the full line portions of the drawings.

We claim:

The ornamental design for a clamp-around ammeter-voltmeter, as shown and described.
